CLAIM

The ornamental design for a knife handle, as shown and described.

DESCRIPTION

FIGS. 1 and 2 are perspective views of the knife handle of our new design;

FIG. 3 is a left side view thereof;

FIG. 4 is a right side view thereof;

FIG. 5 is a bottom view thereof;

FIG. 6 is a top view thereof;

FIG. 7 is a front end view thereof; and,

FIG. 8 is a rear end view thereof.

The phantom lines in the drawings illustrate portions of the knife and handle which form no part of the claim.
